UNITED STATES PATENT OFFICE.

EDWARD C. BALDWIN, OF BOSTON, MASSACHUSETTS.

COMBINED CARTON AND DISPENSER.

1,217,682.

Specification of Letters Patent. Patented Feb. 27, 1917.

Application filed January 8, 1914. Serial No. 811,036.

To all whom it may concern:

Be it known that I, EDWARD C. BALDWIN, of Boston, in the county of Suffolk and State of Massachusetts, have invented certain new and useful Improvements in Combined Cartons and Dispensers, of which the following is a specification.

This invention relates to apparatus for dispensing flat articles, one at a time, and relates particularly to means for enabling individuals to obtain sanitary drinking-cups of the kind illustrated in Letters Patent, No. 1,129,778, granted to me February 23, 1915, for folding drinking-cup, said cups having fins to form handles.

The object of the invention is to provide a device of low cost, and in which the cups can be shipped to the customer, and from which the cups can be removed, one at a time. In other words, the device is practically a shipping package, which is also a dispensing device, so that the cups do not require to be transferred from the wrapper in which they are shipped, into a separate receptacle for delivery to individual users.

Another object is to provide a device of this character which will permit the articles to be removed in either one of the two directions.

To these ends the invention consists in the improvements which I shall proceed to describe and claim.

Of the accompanying drawings,—

Figure 1 is a plan view of a blank which may be folded up to constitute a carton for the cups and which may be also used as a dispensing holder for said cups, thereby rendering it unnecessary to transfer the cups from the carton in which they are shipped into a receptacle from which they may be dispensed.

Fig. 2 is a perspective view illustrating the condition of the device as a carton for the shipment of the cups.

Fig. 3 represents a vertical section through the carton when the latter is supported by a bracket to enable it to be used as a dispenser for the cups, said figure also illustrating reinforcements for the retaining lips.

Fig. 4 is a side elevation of the dispensing carton mounted in a bracket holder.

Fig. 5 represents a section on line 5—5 of Fig. 4.

Similar reference characters indicate similar parts in all the figures.

A vertically elongated box or carton body 12 is preferably made from a blank of paper, pasteboard, or other suitable material, which is folded to a substantially rectangular form in cross section, the lower end being inclined relatively to the longitudinal center of the box, as clearly indicated in the drawings, the upper end having interfoldable flaps 13 to enable the box or carton to be filled with a plurality of paper cups *a*, having fin handles *a'*, such as shown in my patent above referred to. As illustrated by comparing Figs. 1 and 2 the carton may be conveniently made from a blank having side wings one of which has slits and the other has tongues to interengage when the blank is folded from its flat condition to rectangular or box-like form. At one end of the middle portion of the blank, and at one end 75 of one of the side wings, I provide lips 14 which, when the blank is folded to box-like form, are bent toward each other as shown in Figs. 2, 3 and 4. These lips form stops for the edge portions of the cups, leaving a space or opening between said lips through which the bottommost cup can be removed as hereinafter described. The lips are separated from the body of the holder preferably at both ends to form dispensing slits 80 or narrow passageways 15. With this structure the bottommost cup can be removed, either by grasping the fin handle *a'* and pulling the cup directly outward, the cup 85 springing or yielding so that its edges can be withdrawn from behind the lips 14, or by simply sliding the bottommost cup edge-wise, it can be withdrawn through the slits 15, this sliding being effected either by 90 grasping the fin handle *a'* and directing the cup laterally or by pressing the thumb and finger against the bottommost edge of the cup and sliding it outwardly. The reason why the bottommost cup may be removed in the first of the two ways mentioned is 95 that the lips 14 are the only stops for retaining the articles, and the inside distance from one side to the other side exceeds the length of the articles. In other words the length of the passageway which exists between the lips 14 is greater than the length 100 of the articles *a*. It will therefore be understood that the articles can be removed from the carton in either of the two ways mentioned, the first way being by very 105 slightly bending them along the longitudinal center, to pull them out between the

14, and the other way by simply sliding them through the slits 15.

The box or body of the carton is made of comparatively cheap material, and the lips 14 would be liable to open downwardly too freely, if not reinforced. This reinforcing may be effected in either one of several ways. In Fig. 3 I illustrate the reinforcement as consisting of a strip 16 fitting against the 10 lower surface of the front wall of the carton and extending under the upper lip 14, another strip 17 fitting the back of the acute angled lower portion of the carton and extending under the lower lip 14. These reinforcements 16, 17 may be permanently secured in the locations illustrated and described by any suitable means, such as by crimping.

When the box 12 is filled with the cups 20 and is shipped to a customer, suitable rupturable strips 18 are attached, so as to hold the cups and prevent them from being forced directly outward through the opening between the lips 14. Said strips 18 preferably consist of strong paper slips, glued at their ends, but so that they can be readily torn away when the customer puts the dispenser up in position for users to withdraw individual cups.

30 Various devices may be employed to support the carton in the dispensing position. One method is illustrated in Fig. 3. For this purpose I provide the carton with upper and lower parallel slits 19. A bracket 35 having a base 20 and formed with upper and lower tongues 21, 22, may be secured to any suitable support as by means of screws 23. The carton filled with cups may be simply hung upon the bracket by engaging the slits 19 with the tongues 21, 22. The user may then simply rupture the strips 18 if it be desired to remove the cups by grasping the fin handles α' and sliding the lowermost cup α to the right or to the left. Of course, 45 if the removal of the lowermost cup is to be effected by a friction pull against any portion of its surface, the strips 18 need not be ruptured.

50 Another form of combined reinforcement and support for the dispensing box or carton is illustrated in Figs. 4 and 5 which represent a bracket consisting of a piece of sheet metal bent to form a web 26 of double thickness, the edges being bent outwardly to form attaching flanges 27, the sheet metal being also bent to form a pocket 28, rectangular in cross section, to receive the box 12, the lower end of the pocket 28 having flanges 29, 30 which project inwardly toward each other to serve the double purpose of preventing the box 12 from sliding through the pocket, and to reinforce the bottom lips 14 of the box 12.

65 The chief reason for having the lower end of the carton-dispenser inclined at one end,

which end is the lower end in use, is that a person desiring to remove an envelop can more readily see the fin handle α' , and can more readily remove the cup, than if the lower end were horizontal, especially when 70 the carton-dispenser is supported in such location that the lower end would be below the plane of the eyes of the person desiring a cup.

It is to be understood that I do not limit myself to the particular style of blank employed for making the carton, or to the mere location of the slits 19 in the middle portion of the blank, or to the employment of the slits 15. Of course, when the device is supported as indicated in Fig. 4, no slits 19 are required in the blank.

75 Preferably the reinforcing strips 16, 17, when used, are made of suitable metal, and are applied to the blank flat, to be later bent simultaneously with the lips 14. As indicated by dotted lines in Fig. 1, such strips are wider than the lips 14 and may be secured by means of integral tongues 31 forced through the material of the blank and 80 clenched.

85 By my invention I have provided a complete box or container, capable of holding the cups during transportation, and ready for use as a dispenser without alteration 90 other than the removal of the strips 18.

95 Since gravity is depended upon to insure the cups reaching dispensing position, the carton or receptacle is supported in a substantially vertical position. Consequently 100 the inclination of the lower end enables the fin α' of the bottom cup to be seen and readily taken hold of to pull that cup out.

105 I do not claim herein a sanitary cup container in combination with flat paper cups having fins, said container being formed with a slot or opening in its bottom of less area than the aforesaid cup through which opening or slot the fin of the lowermost of a pile of said cups in the container is successively accessible to permit of grasping said 110 fin and removing said cup, for the purpose specified, as the same is claimed in my application #782,157 filed July 31, 1913.

115 I claim:

1. A carton for flat paper articles adapted to be shipped with said articles securely held therein, said carton comprising a single blank folded to form four continuous side walls and an end closure composed of inter-folded flaps, the other end having lips extending toward each other from two of the side walls, a space or opening being provided between said lips through which the articles may be removed singly by bending them, means being provided for preventing the weight of the articles in the carton, or the act of removing them through said opening, from bending the lips outwardly from their retaining positions.

2. A carton for flat paper articles adapted
to be shipped with said articles securely held
therein, said carton comprising a single
5 blank folded to form four continuous side
walls and an end closure composed of inter-
folded flaps, the other end having lips ex-
tending toward each other from two of the
side walls, a space or opening being pro-
vided between said lips through which the
10 articles may be removed singly by bending
them, said lips being reinforced to prevent
them from being bent outwardly by the
weight of the articles in the carton or the
act of removing them through said opening.
15 3. A blank for making a carton for flat

flexible articles, said blank having interen-
gaging wings and having two lips project-
ing in the same direction from a mid-width
portion and from one wing of the blank to
present two parallel and separated retain-
ing lips when the blank is folded to carton
form, the portions of the blank having said
lips being provided with reinforcing mem-
bers. 20

In testimony whereof I have affixed my 25
signature, in presence of two witnesses.

EDWARD C. BALDWIN.
